RADIO RECEIVING APPARATUS

Application filed July 16, 1927. Serial No. 206,168.

The present invention relates generally to certain improvements in radio broadcast receivers and more particularly to means for improving the stability and frequency range of radio frequency amplifiers employed in such receivers.

In trying to use the well known vacuum tube amplifier efficiently, at radio frequencies especially, certain difficulties are encountered which it is the purpose of this invention to overcome.

In the drawings, Fig. 1 represents one unit of a radio frequency amplifier, using the triode T, with its filament F, plate P and grid G. The input circuit of the triode consists of the coil L₁ and variable condenser C₁. In the plate circuit of the triode, there is contained the coil L₂ which will generally be magnetically coupled to the input circuit of another triode. The coil L₁ will generally be magnetically coupled to an antenna circuit.

Fig. 2 shows a slight modification of the arrangement of Fig. 1; the electrical action is practically the same as that of Fig. 1, but the mechanical arrangement of the parts is sometimes more convenient.

Figs. 3 and 4 show alternatives for the arrangement of Fig. 2; they are electrically equivalent but permit a slight mechanical advantage in some wiring schemes.

Referring to Fig. 1, my inventive idea is exemplified in the arrangement of the connection between the input circuit L₁—C₁ and the grid-filament elements of the triode. Instead of connecting the tuned input circuit to the grid directly there is arranged between the input circuit and grid the combination of two resistances R₁ and R₂ and a condenser C₂. The effect of this arrangement is two-fold; it results in a wider frequency range for the circuit than does the ordinary connection and it produces stabilization of the amplifying action.

There are two capacities inside the triode which result in troublesome performance. The capacity between the grid and plate produces the now well-known tendency to set up persistent oscillations in the L₁—C₁ circuit. The effect of my special grid circuit arrange-

ment is to reduce and stabilize the regenerative effect of the triode acting through the grid plate capacity.

This stabilizing action is accomplished by the combined action of the two resistances R₁ and R₂ and the condenser C₂. The proper proportioning of these resistances and capacity depend upon the characteristics of the triode and the frequency range the set is designed to cover. It also depends somewhat upon the types of coils and condensers used for L₁ and C₁.

In addition to producing stabilization this arrangement increases the frequency range of the set by decreasing the effect of the grid-filament capacity of the triode upon the tuning of the circuit L₁—C₁. Although small, this triode capacity has a comparatively large effect upon the highest frequency to which the L₁—C₁ circuit can be tuned, because at the highest frequency the capacity of condenser C₁ is adjusted for its lowest value. Now this input circuit (grid-filament) of the triode is generally in parallel with condenser C₁ and will thus effectively limit the minimum value of capacity in the tuned circuit.

In my arrangement the condenser C₂ is in series with the grid-filament capacity of the triode. As the capacity of two condensers in series is less than that of one alone, this arrangement of condenser C₂ materially reduces the tuning effect of the grid-filament capacity of the triode and makes it possible to tune to higher frequencies.

Whereas I have shown, in Fig. 1, the combination circuit, (R₂ in series with the parallel combination of R₁ and C₂) connected directly between the grid G of the triode and the tuned circuit L₁—C₁, it will be appreciated by those skilled in the art that an equivalent arrangement might be obtained by interchanging the relative positions of the biasing battery B₃ and the combination circuit. Whereas such an arrangement would operate in much the same manner as that shown in my drawings, it has certain objectionable characteristics due to the stray capacities of the circuit.

It will furthermore be appreciated by those skilled in the art that the combination

circuit ($R_1-C_2-R_2$) might be put directly in series with the biasing battery B_3 and this arrangement be inserted between points N—G of the circuit or points M—O of the circuit, or the battery B_3 may be dispensed with altogether and the resistance R_2 be left between points N—G, and the C_2-R_1 circuit be placed between N and G. All of these arrangements will function in much the same manner, some being preferable to others because of the effects of stray capacities in the circuit.

It will be further understood that the resistances R_1 and R_2 may possibly be fractional parts of the same physical resistance unit although I have not found this arrangement as satisfactory as that utilizing two different resistance units. It will be further appreciated that whereas I have shown the condenser C_2 as a physical entity, apart from the resistance R_1 , it is possible to so construct the resistance R_1 , to obtain the capacity C_2 inherent in the structure of R_1 . Such a scheme I have not found as useful as the one shown in my drawings where an actual condenser is shown for C_2 . It may be necessary to use different values of C_2 for different tubes and circuit conditions; whereas it is difficult to change inherent capacities an actual condenser C_2 may have its capacity changed at will.

Another embodiment of my invention is shown in Fig. 2, in which I use the same elements as for Fig. 1, but dispose them in a somewhat different manner. The resistance R_2 and the condenser C_2 , are arranged between the tuned input circuit and the grid as in Fig. 1, but the resistance R_1 I place between the grid and filament circuit. In series with this resistance R_1 I may or may not use a suitable biasing battery for adjusting the average grid potential; the arrangement of Fig. 1 may also be used with or without the biasing battery as desired. The circuit modification as given in Fig. 2 functions in practically the same manner as does Fig. 1, but the mechanical assembly of the parts is sometimes more convenient.

In Figs. 3 and 4, I have shown slight modifications of the arrangement of Fig. 2; the electrical operation is essentially the same as that of Fig. 2 but the mechanical arrangement of the connections is sometimes more convenient.

Although it will be understood that I do not intend to limit myself to any particular values of resistances and capacity, for the guidance of those who endeavor to carry out the ideas of this invention, I have found that with the arrangement of Fig. 1 and with the ordinary triodes in use today as amplifiers suitable values are three megohms for R_1 , 1000 ohms for R_2 , and 25 micro-microfarads for C_2 .

The words "triode", "audion", etc., as used

herein, are to be understood only as convenient identifying terms for any multi-electrode vacuum tubes that it may be found desirable to employ and not as an intended limitation to the ordinary three electrode tubes which have heretofore been extensively used.

Having thus described my invention, what I claim is:

1. In a radio frequency amplifier using a triode vacuum tube, the combination of a tuned input circuit, an inductively reactive plate circuit, two resistances in series between the grid and tuned input circuit, and means for paralleling part of such resistance by a capacity path.

2. In a tuned radio frequency amplifier the combination of an audion, a tuned input circuit, an inductive plate circuit, requisite resistance in series with the lead connecting the grid of the audion to the tuned input circuit and means for paralleling part of such resistance by a capacity path.

3. In a tuned radio frequency amplifier, the combination of an audion, a tuned input circuit, an inductive plate circuit and two resistances in series between the grid of the audion and the tuned input circuit, one of said resistances being so constructed as to provide an inherent capacity sufficiently great that the current through the capacity is greater than the current through the resistance.

4. In a tuned radio frequency amplifier utilizing an audion, means for improving the stability and frequency range of the amplifier, said means comprising requisite resistance and a condenser in the grid lead, said resistance and condenser being associated to cooperate with each other, and said condenser having a capacity of approximately the same value as that of the input circuit of the audion.

5. The combination of a triode, having a coil in its plate circuit and a tuned input circuit connected to the grid-filament terminals, resistances in series with the grid lead, said resistances being in part shunted by a condenser of capacity substantially the same as that of the input circuit of the triode.

6. A radio frequency amplifier utilizing a triode, having a tuned circuit connected to the grid and filament terminals, and a coil connected in the plate circuit, resistances connected between the input circuit of the triode and tuned input circuit, said resistance being shunted in part by a condenser of capacity substantially the same as that of the input circuit of the triode.

PERCIVAL D. LOWELL.
